DEVICE FOR PURIFYING, COOLING, AND
MIXING GASES

Max Aurig, Munich, Germany

Application July 27, 1938, Serial No. 221,517
In Germany July 29, 1937

1 Claim. (Cl. 261—83)

This invention relates to a disintegrator device for purifying, cooling and mixing gases, of the general type disclosed in U. S. Patent No. 1,052,188, granted to Hans Eduard Theisen on February 4, 1913.

In the known types of disintegrator-like gas washers the inner structure comprises stationary baskets, usually consisting of a plurality of rows of round bars, and rotary baskets made up either 10 of rounds or tubes or of flat or angle bars. Outside the rotary baskets vanes are provided to draw or force the gas to be cleaned through the apparatus and to produce a greater or lesser increase in pressure for conveying the purified gas.

15 The rotary bars themselves produce also a certain increase in pressure which depends upon their shape, round bars or tubes having the least effect in this respect. Angle bars also produce little pressure owing to the formation of aerodynamically unfavorable eddies which tend to decrease the generation of pressure. Flat bars yield the relatively best results. This increase in pressure can be computed according to the following formula:

$$\frac{u_2^2 - u_1^2}{g}$$

25 u_2 representing the peripheral speed of the bar relative to the outer diameter d_2 ;
30 u_1 , the peripheral speed of the bar relative to the inner diameter d_1 ; and
35 g , the acceleration due to gravity.

The increase in pressure obtainable thereby is, however, so slight that special vane arrangements 35 are required to subject the gas to be cleaned to more or less pressure.

In contrast with this known construction, it is an object of the present invention to construct the rotary disintegrator bars in such manner that they can simultaneously serve effectively 40 as disintegrator members and as pressure generating members.

The invention is illustrated by way of example in the accompanying drawings, in which

45 Figure 1 is a pressure diagram relating to the use of one form of disintegrator bar according to the present invention;

Fig. 2 is a partial view of a disintegrator having stationary bars and a rotary basket provided 50 with bars according to an embodiment of this invention;

Fig. 3 is a section on the line II—II, of Fig. 2; and

Fig. 4 is a view of a bar system seen from above. 55 According to the present invention, as illus-

trated diagrammatically in Fig. 1, the rotary disintegrator bars are constructed in such manner that they simultaneously serve as disintegrator and pressure generating members, by being curved like fan blades. The angle of outlet α_2 shown in Fig. 1 may amount to 90° , or may be greater or smaller than that, the maximum increase in pressure being attained when the angle α_2 is smaller than 90° . The generation of pressure by such a bar is computed according to the formula

$$\frac{u_2^2 - u_1^2}{g} + \frac{u_2 w_2 \cos \alpha_2 + u_1 w_1 \cos \alpha_1}{g}$$

The use in the purifying device of a disintegrator gas washer as pressure generator permits me to dispense with the special pressure vanes outside the disintegrator, or at least to make them much smaller. Since the speed of the washing liquid injected into the gas washer must be brought up to the circumferential speed of the 20 extreme diameter of the rotor, at the expenditure of a considerable portion of the power required for the washer, a reduction of the outer diameter of the rotor naturally essentially affects the 25 general power consumption of the washer.

A further saving in power is effected owing to the fact that the curved rotating disintegrator bars provide better conditions of flow for both the 30 gas and the washing liquid, at a lower loss due to impact than in the case of the usual round, flat or angle bars, etc.

In case considerations of strength do not permit the use of bars extending over the entire width of high speed apparatus, the curved bars 35 can be subdivided several times according to the intensity of stress and the quality of the material employed.

In the construction shown in Fig. 2, 1 is a shaft on which a disc 2 is placed to which the 40 rotary bars 3 are secured at one end, for instance, as indicated in Fig. 4, by means of the straps 4 and screws 5, so as to form a circle. When they continuously extend over the entire cross section of the washer, the bars 3 are held together at the other end by means of rings 6. In case 45 of larger dimensions the bars 3 are preferably subdivided and thus comprise a plurality of units, as shown in Figs. 2 to 4. Fig. 4 in particular indicates that several rings 7, in addition to the outer ring 6, are required to hold between 50 them bar portions 8. The form of these bars, shown in Fig. 3, is chosen in view of the fact that they are adapted to produce pressure in the apparatus. Consequently, the various bar members 8 have a curved shape and are provided at their 55

ends with straps 4, angularly projecting to one side or the other, by means of which the members 8 are riveted or otherwise secured to the rings 6. Between these bar systems, cooperating in the rotation of the shaft 1 and disc 2, a stationary bar structure is provided. This structure comprises a disc 9 inserted in a casing 10 of the device and having secured to it bars 11 which are externally held together by rings 12. These bars may have any desired form and comprise, for instance, tubes, flat or angle bars, etc. This stationary structure, however, is not absolutely necessary unless, for instance, very exacting demands have to be met as to the purity of the gas. Otherwise, the washer may be equipped

only with rotating bar systems constructed so as to be capable of acting as pressure producing members. The individual and general arrangement of the bar systems may be as described.

I claim:

A disintegrator device for cleaning, cooling or mixing gases comprising a plurality of spaced annularly arranged sets of spaced rotary bars and intermediate annularly arranged sets of spaced stationary bars, between which gas and liquid are passed, said rotary bars being curved in cross-section, in the form of curved fan blades, so as to discharge the gas and liquid at increased pressure.

MAX AURIG. 15
